DAVID GESSNER, OF WORCESTER, MASSACHUSETTS.

MEANS FOR SEALING THE ENDS OF ROLLS OF CLOTH.

1,136,224.

Specification of Letters Patent. Patented Apr. 20, 1915.

Application filed April 9, 1912. Serial No. 639,681.

To all whom it may concern:

Be it known that I, DAVID GESSNER, a citizen of the United States, and a resident of Worcester, in the county of Worcester and state of Massachusetts, have invented certain new and useful Improvements in Means for Sealing the Ends of Rolls of Cloth, of which the following is a specification.

My invention relates to new and useful improvements in means for sealing the ends of rolls of cloth in preparing them for wet treatment, such as given by the apparatus of my Patent No. 988,703, April 4, 1911.

In my said patent I have shown and described a new and improved apparatus for wet-treating cloth in roll form, it being understood that the cloth must first be wound upon a perforated receiving cylinder before being placed into the said apparatus.

The perforated receiving cylinder 30 is shown in the drawings of said patent without any cloth wound upon it, because the winding on of the cloth upon this cylinder before wet-treating, and sometimes also the 25 unwinding of the cloth therefrom after wet-treating, is done in a separate and different machine, such for instance, as illustrated in my Patent #994,075, May 30, 1911.

After winding the cloth upon a perforated receiving cylinder, for wet treatment, a few yards of cotton cloth are wrapped on the outside of it as a means for protection. The cotton wrapper used for this purpose is usually considerably wider than the cloth, and the protruding ends of the wrapper are well drawn down over the ends of the cloth roll, so as to protect them as thoroughly as possible, a rope being used generally for tying down the wrapper outside the cloth roll and the ends thereof. This tying down of the wrapper has to be done by an experienced and clever hand, if the wet treatment following it is to result satisfactorily. When the tying is done slovenly, or imperfectly, unevenness of work is sure to follow, such goods showing uneven shading when subsequently dyed any other color than black. The thing for the operator to observe then at all times, according to the old practice, is to tie the rope at the ends of the roll in such a manner as to make it impossible for the water, when pumped through the perforated receiving cylinder, to issue with greater force or freedom from or through the ends of the roll of cloth, than through, or from the rest of the body of the cloth roll. It is

very difficult to obtain operators who can do this work satisfactorily, and when done properly much time has to be spent over the job, and that means a very small production. Hence, most mills keep on dyeing the bulk of their goods black, whereas they would put out many more light colors, if only they could get uniform results in dyeing. To escape this continuous trouble of uneven shading of colors certain mills resort to dyeing their goods before wet-treating them. In that case, however, the goods shrink too much in dyeing, for the main object of wet-treating is to "set" them so they shall not shrink too much in the subsequent process of dyeing.

Now, the object of my present invention is to enable the mill man to properly wet-treat the goods without fear of uneven shading of colors later on, and which will not require the labor of skilled operators, but which will make it possible for an inexperienced man to give even superior results, and furnish a decidedly greater amount of work, than can be accomplished by the most expert mill hand who has to resort to the methods heretofore known, and heretofore in vogue, for tying down the wrappers of cloth rolls for wet-treatment.

To carry out my invention I preferably employ, near the ends of the cloth-receiving roll, a pair of detachable circular heads, preferably made in sections, that can be bolted together along their division lines and thus be made to grip tightly around the cloth-receiving roll body, just beyond, and in close proximity to the selvages of the cloth and the overlapping wrapper, the union between these heads and the roll body being preferably rendered absolutely air and water tight, when the sections are assembled in place. These heads have circular faces for receiving a layer of flexible band or tape, shown as being preferably of equal width with the width of these faces, and carry flanges preferably extending radially of the heads outward from these faces for guidance, so as to insure the various lengths of tape to lie in a straight circular line, during winding, and thereafter. Different sizes of heads, and different lengths of tape are employed to accommodate varying diameters of cloth rolls, formed either larger or smaller, by the ever changing weights, thicknesses, or lengths of material presented for treatment. My object for winding variable

layers of a flexible band or tape around the faces of these circular heads is to always build up their diameters until they shall equal that of the cloth roll with its 5 rounding wrapper, so that, once these diameters are flush, or in line with each other, I may easily and safely bridge over the intervening gap between the ends of the cloth roll and the adjoining heads by connecting 10 to the tape covering the faces of the heads, a bridge-band sufficiently wide to cover not only the tape-covered faces of the heads themselves, but covering also, and binding down, the margins of the enwrapped cloth-roll, for a distance reaching slightly beyond 15 its selvages in order to thus securely seat up its ends and to make certain, when the water is pumped through the cloth-roll, that it must issue directly through it radially, without escaping at the sides, or ends thereof.

I have fully and clearly illustrated my invention in the accompanying drawings, to be taken as a part of this specification, and 20 wherein;

Figure 1, shows in cross-section one of the 30 perforated cloth-receiving cylinders 30, used in a wet-treating apparatus such as described in my Patent No. 988,703, with a number of pieces of cloth wound upon it and encircled by a cotton wrapper turned down at the sides, and placed against the ends of the cloth-roll may be seen the sections of two circular sealing-heads with a 35 layer of tape wound upon their faces and a bridge-band drawn over the tape and the edges of the enwrapped cloth-roll, shown in cross-section; Fig. 2, represents two sections of the circular sealing-head bolted together 40 with a portion of the web and flange of one section removed, thus exposing to view part of its face shown in cross-section; Fig. 3, is a front view of one section of a sealing-head, with the tie-bolts thrown back; Fig. 4, 45 simply shows an enlarged cross-sectional view of the corner of a cloth-roll and its adjacent sealing-head with tape and bridge-band in place; Fig. 5, shows a detail.

Referring to the figures of the drawings 50 just mentioned, 30 is the perforated cloth-receiving cylinder, upon which are wound in roll-form one or more pieces of cloth *a*, around which cloth-roll are lapped several layers of a cotton-wrapper *b*, with its overhanging ends *c* turned down over the edges of the cloth. The circular sealing-heads *d* are so placed upon the perforated cylinder 30 as to bring the inner edge *e* of the annular face *f* of the heads close up to and in 55 engagement with the turned down ends *c* of the wrapper, leaving an open space *g* between the web *h* of the heads and the ends of the cloth roll. The face *f* on each head is 60 preferably provided by forming the inner face of the head with an inwardly-project-

ing annular flange the outer cylindrical surface of which constitutes said face *f*. The heads are preferably made in separable sections, formed with radial abutting flanges *d'* 70 adapted to be clamped together by any suitable means, as for instance, the swing-bolts *d*, pivoted to one of said sections and adapted to engage the other section and be clamped thereto by nuts on said bolts, whereby said sections are clamped around 75 the cloth-roll. The sections *d* are formed with curved recesses *d*² at their central portion, which, when the sections are assembled combine to form a circular opening within 80 which the cloth-roll 30 is received. By the arrangement described of securing the heads on the roll they are readily adjustable lengthwise of the roll to cloth of different widths. Each of the heads *d* is extended beyond the face *f* to provide a circumferential radial flange *d*⁴ which is spaced from the end of the cloth when the edge *e* is 85 engaged with the cloth.

The annular face *f* has a shallow peripheral groove *i* cut around its middle portion, and contains a number of undercut V-shaped pockets *l* spaced around its periphery and extending transversely of said face, into any of which pockets may be engaged the end of a hook *m* (see Fig. 5) 90 fastened at the extreme end of the band or tape *n* for covering the face *f* of the sealing-heads, and filling the space between the outer edge portion of the heads, that is the flanges *d*⁴ and the ends of the cloth roll. 100 Fastened to the under side of the band or tape *n*, and extending for a length equal to the circumference of the face of the sealing-head, is a narrower piece of tape, or tongue *o*, which practically fills the shallow groove *i* when the hook *m* is inserted into 105 one of the pockets *l* in the face of the sealing-head whenever the tape is wound around it. By this arrangement the pressure of the tape against the edges of the groove assists in making an efficient seal between the 110 said face and the tape, and the operator is able to start the tape straight when winding it in place. At the other extremity of the tape *n* are secured the eyes *p*, which engage with the hooks *q* fastened upon the inner or the starting-end of the bridge-band *r*, which is drawn down tightly around the tape *n*, and the corners of the enwrapped cloth-roll, thus bridging-over and completely sealing the joint or crack between 115 the ends of the cloth roll and the heads. Although not shown in the drawings, a canvas belt with a buckle or any other fastening means may be employed outside of the bridge-band to keep its end from slipping and the band from losing its grip around the face-tape *n* of the sealing-heads *d* and the end of the enwrapped cloth-roll.

For conveniently lifting a cloth-loaded 120

cylinder 30, I place around the flanges *d* of the heads a steel rim or ring *s* secured by screws *u*, and form openings *t* in the flanges *d*, so that a hook from the lifting-chain of 5 a crane may be inserted under the steel rim *s*, which is made amply strong to sustain any weight ever likely to be put upon it.

In the operation of apparatus such as 10 shown and described in my Patent No. 988,703, after a cloth-loaded perforated cylinder 30 has been put into place, water is turned on until the cloth roll is completely submerged in it, whereupon a pump is operated for drawing the water surrounding the 15 cloth-roll through the layers of cloth surrounding the perforations of the cylinder until exhausted. When the ends of such a cloth-roll are effectively sealed, as just described, the water surrounding it will work 20 inward and fill the spaces *g*, but as soon as these are filled, the water will be drawn steadily and straight toward and through the perforations in the cylinder 30. Reversely, when water is pumped into the 25 interior of cylinder 30 it will quickly fill the spaces *g*, but once filled, the water in these spaces will form as solid a resistance to any further onrush of water issuing from the 30 perforations underneath the cloth, as the walls of the sealing-heads themselves offer, and once the spaces *g* are filled, all following water will be forced straight toward the outside of the enwrapped cloth-roll wherever it is not sealed by the bridge-bands *r*. 35 Thus I get a uniform treatment of the fabric, no matter in what direction the pumps may be working, and when a fabric so treated is dyed afterward, no uneven shading of colors will result, as is the case where the 40 tying of the end of a cloth roll with its wrapper is left to the ingenuity of a skilled workman, who depends upon the winding of a mere rope for sealing the ends, with disastrous results, except where black colors 45 only are concerned.

What I claim and desire to secure by Letters Patent of the United States is:—

1. In combination, a perforated receiving cylinder, and sealing means for the end of a 50 roll of cloth wound thereon, comprising a head mounted on the cylinder, detachable bridge means to seal the space between said head and the adjacent end of a roll of cloth, and means on the head to support said 55 bridge means.

2. In combination, a perforated receiving cylinder, and sealing means for the end of a 60 roll of cloth wound thereon, comprising a head mounted on the cylinder, and bridge- means to seal the space between said head and the adjacent end of the roll of cloth, said bridge-means consisting of a flexible band.

3. In combination, a perforated receiving 65 cylinder, and sealing means for the end of a

roll of cloth wound thereon, comprising a sectional head mounted on the cylinder, and bridge-means, to seal the space between the said head and the adjacent end of the roll of cloth.

4. In combination, a perforated receiving cylinder, and sealing means for the end of a roll of cloth wound thereon, said means comprising a head having a laterally projecting annular flange adapted to engage the 70 end face of a roll of cloth to hold a wrapper in engagement therewith, and detachable means for sealing the space between the head and the end face of the cloth roll.

5. In combination, a perforated receiving cylinder, and sealing means for the end of a roll of cloth wound thereon, comprising a head mounted on and adapted to be detachably connected to said perforated cylinder, and means for bridging the space between 80 the head and the adjacent end of the roll of cloth.

6. In combination, a perforated receiving cylinder, and sealing means for the end of a roll of cloth wound thereon, comprising a 90 head detachably connected to and adjustable lengthwise of the cylinder, and means for bridging the space between said head and the adjacent end of the roll of cloth.

7. In combination, a perforated receiving cylinder, and sealing means for the end of a roll of cloth wound thereon, comprising a head, means for bridging the space between said head and the adjacent end of a roll of cloth wound on the receiving-cylinder, said 100 head having pockets at the periphery thereof, and a rim member bridging said pockets.

8. In combination, a perforated receiving cylinder provided with heads having annular inwardly-projecting faces, and radial 105 flanges, a filler-band adapted to be wound on each face between the end of a roll of cloth wound between said heads, and said radial flanges, and a bridge-band adapted to be wound over each filling-band and the adjacent end of the roll of cloth.

9. In combination, a perforated receiving cylinder, and sealing means for the end of a roll of cloth wound thereon, comprising a head having an annular face, having a peripheral groove, and a flexible member 115 adapted to be wound on said face and having a tongue to enter said groove.

10. In combination, a perforated receiving cylinder, and sealing means for the end 120 of a roll of cloth wound thereon, comprising a head having an annular face having an undercut pocket and a peripheral groove leading therefrom, and a flexible member adapted to be wound on said face and having an attaching device to engage said undercut pocket and a tongue to enter said peripheral groove.

11. In combination, a perforated receiving cylinder, and sealing means for the end 130

- of a roll of cloth wound thereon, comprising a head having an annular face adapted to be located between said head and the end of the roll of cloth, a flexible filling-band adapted to be wound on said face, and a bridge-band of greater width than said filling-band adapted to be wound on said filling-band and the adjacent part of the roll of cloth.
12. In combination, a perforated receiving-cylinder, and sealing means for the end of a roll of cloth wound thereon, comprising a head having an annular face adapted to be located between said head and the end of the roll of cloth, a flexible filling-band adapted to be wound on said face, and a bridge-band of greater width than said filling-band adapted to be wound on said filling-band and the adjacent part of the roll of cloth, said bridge-band being detachably connected to the flexible filling-band.
13. In combination, a perforated receiving-cylinder provided with heads having annular faces, and bridge members adapted to engage said faces and extend over the ends of the cloth wound on the cylinder between said heads.
14. In combination, a perforated receiving-cylinder provided with heads having annular faces, filling means to fill the space between said faces and the circumference of cloth wound between the heads, and a bridge-member to cover said filling means and the adjacent edge of the cloth.
15. In combination a perforated receiving-cylinder provided with heads having annular faces, and bridge-bands adapted to engage said faces and extend over the ends of the cloth wound on the cylinder between said heads.
16. In combination, a perforated receiving cylinder, and sealing means for the end of a roll of cloth wound thereon, comprising a head having a laterally-projecting annular flange member adapted to hold the wrapper about the roll of cloth in engagement with the end of said roll, and detachable filling means to bridge the space between the cloth and the head.
17. Sealing means for the end of a cloth-roll, comprising a head having an inwardly-projecting annular flange adapted to take position concentric with the roll but spaced
- radially from the circumference of the roll, and a circumferential radial flange projecting beyond said first-named flange.
18. Sealing means for the end of a cloth-roll, comprising a head having an inwardly-projecting annular flange and a circumferential radial flange projecting beyond said first-named flange, and a flexible detachable sealing member adapted to be supported on the outer surface of said first-named flange.
19. In combination, a perforated receiving cylinder, and sealing means for the end of a roll of cloth wound thereon, said means comprising a head having a laterally-projecting annular flange, spaced from the cylinder, and adapted to engage the end face of a roll of cloth to hold a wrapper in engagement therewith, detachable means for sealing the space between the head and the end face of the cloth-roll, and detachable means for sealing the joint between said first-named detachable means and the cloth-roll.
20. In combination, a perforated receiving cylinder, and sealing means for the end of a roll of cloth wound thereon, said means comprising a head having a laterally-projecting annular flange, spaced from the cylinder, and adapted to engage the end face of a roll of cloth to hold a wrapper in engagement therewith, detachable means for sealing the space between the head and the end face of the cloth-roll, and detachable means for sealing the joint between said first-named detachable means and the cloth-roll, each of said detachable means consisting of a flexible band.
21. A sealing means of the character described consisting of a head adapted to be secured about a cloth-receiving roll, said head having an annular laterally-projecting flange, and a radial circumferential flange, and a flexible bridge-band adapted to be wound around said first-named flange to fill a space between said second flange and a roll of cloth.

In testimony whereof I have hereunto signed my name in the presence of two subscribing witnesses.

DAVID GESSNER.

Witnesses:

M. E. McNINCH,
C. G. HEYLMUR.

It is hereby certified that in Letters Patent No. 1,136,224, granted April 20, 1915, upon the application of David Gessner, of Worcester, Massachusetts, for an improvement in "Means for Sealing the Ends of Rolls of Cloth," an error appears in the printed specification requiring correction as follows: Page 2, line 16, for the word "seat" read *seal*; and that the said Letters Patent should be read with this correction therein that the same may conform to the record of the case in the Patent Office.

Signed and sealed this 11th day of May, A. D., 1915.

[SEAL.]

R. F. WHITEHEAD,
Acting Commissioner of Patents
